BAND RETAINED STAND-OFF MOUNTING

Paul J. Gorishek, East Moline, Ill., assignor to Gulf +
Western Industries, Inc., New York, N.Y.

Filed July 26, 1972, Ser. No. 275,245

Term of patent 14 years

Int. Cl. D8—08

U.S. Cl. D8—234

FIG. 1

FIG. 2

FIG. 3

FIG. 4

FIG. 1 is a plan of band retained stand-off mounting showing a surface which may be the top surface or the bottom surface;

FIG. 2 is a side elevation view showing the symmetrical characteristics thereof;

FIG. 3 is a perspective view showing the heel of the mounting and part of the top or bottom surfaces; and

FIG. 4 is a perspective view showing the toe of the mounting and the top or bottom surfaces, with the toe of the mounting cut-away, in section view, to show the interior of the toe.

I claim:

The ornamental design for a band retained stand-off mounting, as shown and described.
